UNITED STATES PATENT OFFICE

CHARLES W. THOMPSON, OF WOLLASTON, MASSACHUSETTS, ASSIGNOR, BY MESNE ASSIGNMENTS, TO STEINER SALES COMPANY, OF SAIT LAKE CITY, UTAH, A CORPORATION OF UTAH

ROLL TOWEL CABINET

Application filed January 24, 1929. Serial No. 334,709.

This invention relates to a towel cabinet, particularly the kind designed to stand on the floor.

One of the objects of this invention is to provide a cabinet that will hold clean toweling in the upper portion and soiled toweling in the lower portion, equipped with a simple, reliable and inexpensive mechanism whereby the toweling pulled out of the cabinet by the user is automatically withdrawn within the cabinet immediately upon its release. Another object is to provide mechanism which limits the length of toweling the user may pull out of the cabinet at one time. I have found that by placing the clean toweling in the upper compartment and the soiled toweling in the lower compartment, the cabinet itself, as well as the mechanism, may be greatly simplified in construction, which in turn makes the insertion of clean toweling easier and more readily understood. Such a simplification is very advantageous because the insertion of clean toweling must often be done by persons who have little mechanical knowledge and short patience with a towel cabinet having mechanism at all complicated.

Another object of my invention is to provide a cabinet so constructed that the towel is within the cabinet, except when being used, but with a portion visible and in a position where it may be easily grasped and pulled out. This not only makes the cabinet more attractive, but also avoids having any part of the toweling outside of the cabinet when not in use, where it would become soiled if not used frequently, as during the night.

With the above and other objects in view which will more readily appear as the nature of the invention is better understood, the same consists in novel construction, combination, and arrangement of parts hereinafter more fully described, claimed, and illustrated in the accompanying drawings.

In accordance with the rules of practice, reference is made to my co-pending application, Serial Number 319,532, filing date November 15th, 1928.

Like numerals and letters of reference indicate corresponding parts in each figure.

In the drawings,

Figure 1 is a perspective view showing the cabinet ready for operation, the dotted and dash lines indicating position of toweling when pulled out for use.

Figure 2 is a cross section on line 2—2 of Figure 1, and showing the toweling fully connected to the automatic take-up mechanism within the cabinet.

Figure 3 is a front elevation of the cabinet with the door wide open, with parts of the interior broken away.

Figure 4 is a cross section on line 4—4 of Figure 2.

Figure 5 is a cross section on the line 5—5 of Figure 2.

Figure 6 is a perspective view of the elevator.

Figure 7 is a partial cross sectional view on the line 7—7 of Figure 3.

Figure 8 shows the means of connecting two lengths of toweling with a clasp.

As illustrated the towel cabinet, which rests on short legs 14, consists of a bottom 15, a back 16 having perforations 16a in it for ventilating purposes, sides 17, a top 19 having stays 20 which are in contact with the inner surfaces of the back 16 and sides 17 as illustrated in Figure 2 of the drawings. A lower front piece 21 attached to the sides and bottom and a large door 22 complete the frame of the cabinet. This door 22 swings on hinges 23 attached to the side 17. In the upper portion of the door 22, a good sized opening 25 is made, the width of which is slightly greater than the width of the toweling so that the fingers may easily secure a grasp on the edge of the toweling to pull it out. The door is also provided with a locking arrangement 26, and on the inside more than half way down two stops 27 are attached having rubber bumpers 28, the purpose of which will be explained later.

Inside the cabinet is fitted a pair of removable side pieces 30, having cleats 31 on each side running lengthwise which cleats are in contact with the sides 17 when set up. A space is therefore left between each side 17 and the side piece 30 in which space a chain attached to a sprocket mechanism moves, as later explained. These side pieces 30 extend

vertically from just under the top stays 20 to the lower or driven control roll B later referred to. These side pieces 30 are flush against the back 16 and their front edges slant 5 inwardly from top to bottom so that while their front edges are approximately two inches inward from the front edges of the sides 17 at the top, this distance is increased until the distance at the bottom is four inches 10 or more. A crescent-shaped hole 32 is cut in the front half from the top edge downwardly in each of said side pieces 30 just beyond the center, which hole is large enough to permit the upper or driver control roll 15 A, later described, which extends through it, to freely rotate. Still farther towards the front of the cabinet, another hole 33 is cut from the top edges of each of said sides 30 in which hole a shallow slot 33a and a deeper slot 33b is cut in either of which slots the cylindrical towel spacing rod 34 rotatably fits. About half-way down said side pieces 30, a horizontal slot 36 is cut extending from front to back. A dividing shelf 37 fits into these slots 36, which shelf 37 supports the roll of clean toweling 38 and serves to divide the cabinet into an upper compartment C and a lower compartment D, thereby preventing the clean toweling from coming in 30 contact with the roll of soiled toweling 41 which is kept in the lower compartment D. This dividing shelf 37 extends beyond the front edges of the side pieces 30 but not to the front edges of the cabinet sides 17. In the lower half of each of the side pieces 30 a shallow recess 42 is cut which extends horizontally from the front edge approximately $2\frac{1}{4}$ inches, and then extends vertically downward, terminating in a crescent shaped hole 43 similar to the other hole 32, which hole 43 is cut from the bottom edge and is large enough to permit the driven control roll B, which passes through it, to freely rotate. The ends of the winding stick 44, on which the soiled toweling 41 is wound, are slipped into the recesses 42, and the stick is pushed in said recesses 42 until it rests directly on said driven control roll B. As the soiled toweling 41 winds on said stick 44, the roll gradually becomes larger causing the stick 44 to move 50 upwardly in the vertical recesses 42.

The removable side pieces 30 rest directly on side piece supports 45 which are in contact with the inner surfaces of the cabinet bottom 15. These side piece supports 45 are flush with the front edges of said cabinet sides 17, and each has a vertical slot 47 in which the elevator 48, which is part of the automatic towel take-up mechanism, slides. 55

This elevator 48 consists of two end pieces 49, in each of which a vertical slot 50 is cut extending from the top approximately half-way down, and another smaller vertical slot 51 extending from the bottom of the eleva-

tor up about one inch. These end pieces 49 are connected by a center piece 52 which has a piece cut out at each end intermediate the top and bottom which leaves two projections 53 at each end of said center piece 52. These projections 53 extend through the slots 50 and 51 and fit into the vertical slots 47, serving as guides for the elevator 48 as it moves up and down. Near the top of said elevator 48, two cylindrical rods 54 are rotatably mounted in the two end pieces 49, one on each side of the vertical slots 50. When the toweling is not being used, this elevator rests on rubber bumpers 15a attached to the cabinet bottom 15. 70

A cylindrical towel spacing rod 55 is rotatably mounted in shallow holes drilled in the cabinet sides 17 by springing it into said holes. This rod 55 is just above the side piece supports 45 and the soiled toweling comes in contact with it before it is wound on the stick 44. 75

An inner towel door or guard G is mounted in shallow holes drilled in the cabinet sides 17 as explained in detail later. These holes are near the front corners of the dividing shelf 37, so that when the cabinet is ready for use the bottom of said guard G is just below the bottom of said shelf 37, said guard thereby constituting a door for the upper 90 compartment C as it extends to within a few inches of the cabinet top 19. This towel guard G consists of two end bars 57 rounded at the ends in which vertical slots are cut in their rear half, which slots extend most of the way from top to bottom. In these slots a flat board 58 constituting the body of the guard, is permanently mounted, which serves as a protector for the clean toweling in the cabinet and is directly back of the toweling which is visible through the opening 25 in the door 22. A rung 59 is stationarily mounted in the end bars 57 near their top edges so that the top of said rung 59 is just above the top of the flat board 58. The clean 100 toweling passes over this upper rung 59, which is forward of the board 58, and it serves the purpose of giving the toweling a smooth rounded surface to run on as it is pulled out of the upper compartment C. Another rung 60 is stationarily mounted in the end bars 57 near their bottom edges so that the bottom of said rung 60 is just below the bottom of the flat board 58. This lower rung 60 extends through and beyond said end bars 57 and these projecting ends 61 rotatably fit into the shallow holes previously mentioned, which are made in the cabinet sides 17, thereby hingedly mounting said towel guard C to the cabinet, so that when clean toweling is inserted or removed from the upper compartment C this guard or door G may be swung down out of the way and then pushed up again. This rung 60, which is forward 110 of said board 58, like the other rung 59, 115

120

125

130

furnishes a smooth, rounded surface for the toweling to run on as it is automatically pulled within the cabinet when the user releases it. Both of these rods 59 and 60 are in the same vertical plane, being forward of the flat board 58, and hold the toweling away from it, so that there is ample space between the toweling and said board 58 for the user to insert his fingers back of the toweling to grasp it. The width of the toweling is slightly less than the width of this board 58, thereby leaving sufficient space between the end bars 57 and the edge of the toweling for the user to insert his fingers and grasp both sides of the toweling as just explained.

In the upper compartment C just below the stays 20, a driver control or feed roll A is mounted in the cabinet sides 17, while in the lower compartment D slightly below the top of the cylindrical rod 55 a driven control or take-up roll B is mounted, which rolls are of the same construction and cooperate with each other to unwind and wind the toweling T. Each of these control rolls A and B have a body 65, with axles 66 extending therefrom at both ends, which axle is mounted in ball bearings 67 which are mounted in holes 68 cut in the cabinet sides 17. Both of said rolls have a roughened peripheral surface 69 obtained by wrapping emery paper or a sheet of burred metal around the body 65, or the body 65 may be made of metal roughened on the surface. A sprocket wheel 70 is fixedly mounted on the right end of the axle 66 of each roll, said sprocket wheel having teeth 71 on which is mounted a sprocket chain 72, which connects both sprocket wheels 70 so that any motion imparted to either of the rolls moves both. The clean toweling comes in contact with the roughened surface 69 of the control roll A just after it is unwound from the roll 38, while the soiled toweling roll 41 rests upon and is in contact with the roughened surface 69 of the control roll B so that as the clean toweling is unwound, the roll A rotates which drives the chain 72, which in turn drives the control roll, which rotates the soiled toweling roll 41, thereby winding the soiled toweling. These control rolls, A and B, are prevented from moving in more than one direction by a pawl 73 which is pivotally fastened as at 74 to the side of the cabinet 17 near the top, so that the pawl engages the teeth 71 and prevents any winding of the clean toweling and unwinding of the soiled toweling.

It has been found preferable to use lengths of toweling of approximately twenty-five yards, and where the cabinet is of such size as to take more toweling,—the one illustrated takes one hundred yards—a clasp 75 is used, and the loops 74 formed in the ends of each length of toweling are inserted in said clasp to make the toweling T one con-

tinuous length, as shown in Figure 8 of the drawings.

This cabinet is filled and operated as follows:

To insert a supply of clean toweling the cabinet door 22 is unlocked and swung open, and the towel guard G swung down where it hangs suspended opposite the lower compartment D. The clean toweling is inserted in the upper compartment C with the free end towards the front. This end is extended to the front and over the cylindrical towel rod 34, which is temporarily mounted in the slots 33b, and then under and over the driver control roll A. The rod 34 is then slipped into the slots 33a where it remains while the cabinet is in use. The slots 33b are provided so that there may be plenty of space for the hand when putting the toweling under and over the feed roll A. The guard or door G is then swung up, the end of toweling pulled over the upper rung 59 and then downwardly, and the winding stick 44 inserted in the loop 74. The elevator 48 is lifted by hand until the top of its center piece 52 strikes the rod 55 and the stick 44 together with the end of toweling is put through the space between the rod 55 and the two elevator rods 54 from the outside. The elevator is dropped and rests on the rubber bumpers 15a carrying the toweling T with it and forming loops running over the rod 55 and under the elevator rods 54. The stick 44 is slipped into the recesses 42 and pushed in and then down until it rests on the driver control roll B. The toweling should be wound around the winding stick 44 so that it is fairly taut between the clean roll 38 and the soiled roll 41. The door 22 is then closed and locked and the cabinet is ready for use.

The user inserts his hand into the opening 25 and slips his finger between the edge of visible toweling and the end bar 57 of the guard G and then back of the toweling in the space between the toweling and the flat board or body 58 of said guard G. The toweling is grasped and pulled outwardly which causes the elevator 48 to rise until the top of the end pieces 49 strike the rubber bumpers 28 on the stops 27 which are fastened to the door 22. The elevator is held in this position while the toweling is held outside the cabinet by the user in drying himself. As the clean toweling is pulled outwardly the soiled toweling also comes out of the cabinet which furnishes the play so that the user may freely move the clean toweling about when drying himself. The withdrawal of the soiled toweling from the cabinet is possible because of the loops formed between the rod 55 and the two elevator rods 54. As the elevator 48 is raised a portion of this toweling in the loops moves upwardly and outwardly while the other portion is wound on the soiled toweling roll 41. The act of pulling out the clean toweling rotates

the control roll A and through the sprocket and chain mechanism the control roll B is simultaneously rotated which causes the soiled toweling to wind on the soiled toweling roll. When the elevator 48 strikes the bumper 28 this stopping of the elevator prevents any more toweling being pulled out of the cabinet, so, therefore, the length of toweling which may be pulled out of the cabinet 10 is determined by the movement of the elevator, which makes it possible to furnish a definite length for each user. It should be understood, however, that if the toweling is not pulled out, there is nothing to prevent 15 a person from continuously pulling all of the clean toweling off the roll and simultaneously winding it on the roll 41 and thereby wasting it; but he cannot pull out of the cabinet at one time more than a certain length 20 which is predetermined, and as he cannot use the toweling unless he pulls it out, this cabinet provides a practical measured service.

When the user has dried himself he releases 25 the toweling and the elevator drops by gravity to its original position pulling the released toweling within the cabinet. Everything is then in readiness for the next user to dry himself.

30 When the last of the clean toweling is used the door is opened and the roll of soiled toweling is slipped out of the recesses 42, and a clean roll is inserted in the cabinet.

If desired, the automatic take-up mechanism may be disregarded, as the toweling may be inserted and used independent of it, in which case a loop of toweling extends through the opening 25 and hangs outside the door 22 ready for use.

40 What I claim is:—

1. A towel cabinet comprising a casing having a door at the front provided with an opening in the upper portion thereof, side pieces fitting within said casing and spaced 45 from the side walls thereof, a shelf horizontally supported by said side pieces and extending from the back of the casing forwardly to a point near the front thereof and adapted to support a supply of clean towel, 50 bars provided on each side of said casing in front of said side pieces, a guard plate mounted in said bars and extending vertically in front of said shelf and side pieces and in the rear of said door opening, rungs mounted in 55 said side pieces at the top and bottom of said guard and in front of the same, a feed roll mounted in said side pieces in the rear of said guard and over which a web of clean towel may be passed from said supply to 60 said upper rung, a gap being provided between said upper rung and the wall of the door opening through which a towel web may be stretched for convenience of use, said upper and lower rungs holding a towel web 65 out of contact with said guard and a gap be-

ing provided between the lower rung and said door into which a towel web when used may depend.

2. A towel cabinet comprising a casing having a door and an opening in the upper portion thereof, side pieces mounted in said casing and spaced from the side walls, the forward edges of said side pieces slanting inwardly from the top towards the bottom thereof, a shelf supported by said side pieces near the horizontal middle portion thereof and adapted to support a supply of towel, a take up feed roll for the soiled towel interposed between said side pieces below said shelf, a delivery feed roll carried by said side pieces above said shelf and having a driving connection with said take up feed roll in the space between the side wall of the casing and one of said side pieces, the position of the delivery feed roll being such that a web of clean towel may be stretched thereover for delivery to the user through said door opening, a gap being provided between said shelf and door through which a soiled web may depend, a take up roll mounted in said side pieces whereon a towel web may be wound with its convolutions resting on said take up feed roll and an elevator device having a vertical movement between the slanting edges of said side pieces and said door and provided with oppositely spaced rods under which a web of towel may be passed to said take up roll, whereby said web may be drawn taut and the wrinkles removed.

3. A towel cabinet comprising a casing having a door at the front provided with an opening in the upper portion thereof, side pieces fitting within said casing and spaced from the side walls thereof, a shelf horizontally supported by said side pieces and extending forwardly from the rear thereof and adapted to support a supply of clean towel, a guard plate extending vertically in front of said shelf, a rung mounted near the top of said guard plate, a feed roll mounted in the upper portion of said side pieces, vertical slots of different depth being provided in said side pieces between said feed roll and said rung, a cylindrical towel spacing rod rotatably fitting in either of said slots, the position of said rod, said feed roll and said rung being such that a web of towel may be stretched over said rod and around said feed roll to said rung and from thence through the opening in said door to a position convenient for use, a gap being provided between said shelf and door through which the soiled web may depend into the lower portion of said casing.
